UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

PRINTING TELEGRAPHY.

Application filed January 20, 1920. Serial No. 352,875.

To all whom it may concern:

Be it known that I, JOHN H. BELL, a citizen of the United States, residing at South Orange, in the county of Essex, State of New Jersey, have invented certain new and useful Improvements in Printing Telegraphy, of which the following is a full, clear, concise, and exact description.

This invention relates to printing telegraphy and more particularly to printing telegraph receivers in which the characters are printed in a continuous line.

An object of the invention is the provision of a telegraph receiver of the above character wherein there is provided means for effecting the printing of the characters of a message in an efficient and reliable manner.

Another object of the invention is to provide means whereby the impulses are adapted to be stored in a plurality of signal storing means which will be rendered effective alternately for causing the operation of the selecting mechanism controlling the operation of the printing means for printing the characters of a message in a continuous line.

The invention provides a distributor under the control of line current impulses for applying the impulses as transmitted over the line to a first and second group of signal storing means for effectively storing up the signal impulses. The provision of a signal storing means of this sort thereby gives a complete overlap and prevents the wasting of line time in the transmission and distribution of such impulses. A translator switch is also provided for consecutively clearing out the groups of signal storing means and applying the impulses as stored therein to a selecting mechanism for effecting the operation thereof to energize a printing magnet which controls the application of a tape to the characters of a type wheel for the printing of the characters of a message in a continuous line.

In the accompanying drawing Fig. 1 is a diagrammatic representation of the apparatus employed, while Fig. 2 is a perspective showing one form of construction of a printer wherein the characters are adapted to be printed in a continuous line.

The drawing shows a distributor 6 having a rotatable arm 7 carrying a contact brush and which is electrically connected with the armature of the polarized relay 5. This relay is connected to the line 4 which extends

from a distant station at which there is located suitable transmitting apparatus for the transmission of the various impulses representing the characters of a message. This relay is of the polarized type and is adapted to operate in accordance with the current impulses impressed upon the line. The armature of this relay is normally connected with the negative terminal of the battery 9 and is thus connected with the winding of the start magnet 8 through the arm 7 of the distributor 6. The magnet 8 is, however, prevented from operating since there is connected with the magnet winding a source of battery, the polarity of which is such as to oppose the flow of current from the battery 9.

There is associated with the distributor 6 a plurality of groups of signal storing means as represented by the characters A and B respectively. These groups of signal storing means preferably consist of a number of condensers arranged in groups; each condenser being connected with a segment of the distributor 6 so that when the arm 7 sweeps over the various segments, the condensers will be charged according to the polarity of the current as applied thereto through the armature of relay 5, the arm 7 and contact brush of the distributor 6. The groups of signal storing means are arranged so that as soon as a set of character impulses have been received and stored in one group of signal storing means, these same stored impulses may be released to effect the operation of suitable selecting mechanism, while the next or succeeding set of character impulses are being received and stored in another group of signal storing means, thereby providing a complete overlap in the selection of the message character. A discharge path for the various condensers is established through the segments and brushes of the translator switch 21. This translator switch comprises a number of segmented rings C, D, E, F, G and H, shown developed in Fig. 1. The segments of the several rings are of different lengths and there are special segments individual to each of the condensers enumerated above. A translator arm 22 carrying brushes 23, 24 and 25, each of which is individual to a pair of segmented rings is adapted to be moved in a manner which will be presently described for consecutively connecting the signal storing means with the

windings of each of the polarized selecting magnets 26, 27, 28, 29 and 30. The arm 22 of the translator switch is normally held in its unactuated position by means of a holding pawl under the control of magnet 31. The magnet 31 is energized upon the passage of the brush carried by the arm 7 over the segments 61 and 62 to which the winding thereof is connected. The energization of this magnet is thereby effected twice during a complete revolution of the arm 7. Inasmuch as there are two groups of signal storing means associated with the distributor, it is necessary that the translator switch 15 arm 22 complete two cycles to one of the arm 7 of the distributor 6. It is, therefore, arranged so that the magnet 31 will be energized subsequent to the charging of the condensers of each of the groups of signal storing means for effecting the release of arm 22. It is thus seen that the translator switch arm 22 together with the brushes carried thereby will be caused to make two complete cycles to one of the arm 7 for clearing out the two 25 groups of signal storing means connected with the segments of the distributor 6.

Let us assume that the arm 22 of the translator switch is moving in the direction of the arrow and that the condensers in 30 group A of the signal storing means have been charged in accordance with a group of selecting impulses as transmitted over the line 4. There will thus be completed a circuit including the winding of the selecting magnet 26 which may be traced from the terminal of condenser 11, conductor 32, segment 33 of ring G, brush 23, segment 34 of ring H and the winding of the selecting magnet 26 which will thus be energized in 35 accordance with the polarity of the charge on the condenser 11. The circuit for effecting the energization of selecting magnet 27 extends from the terminal of the condenser 12, conductor 35, segment 36 of ring E, brush 24, segment 37 of ring F and the winding of the selecting magnet 27 which will be energized in the same manner as selecting magnet 26. Other condensers are, in a like manner, adapted to be consecutively 40 connected with the windings of each of the selecting magnets 28, 29 and 30 for effecting their operation. After the selecting magnets have thus been energized, a circuit is established including the winding of printing magnet 38. Let us assume, for the sake of clearness, that the armatures of the selecting magnets have all been moved from the positions shown in the drawing thereby closing their front contacts. The energizing 45 circuit of the magnet 38 thus extends from the source of battery 40 through the segment 41, brush 23, segment 42, front contact of magnet 26, front contact of magnet 27, segment 43, brush 24, segment 44, front contact of magnet 28, front contact of magnet 29, segment 45, brush 25, segment 46, front contact of magnet 30, and the winding of printing magnet 38 to ground. The printing magnet 38 will thus be operated to effect the printing of a desired character as will be more clearly brought out in the description which is to follow.

The arm 7 is adapted, after completing a half cycle to be held against rotation by means of the holding pawl controlled by magnet 50, the energizing circuit of which is completed in the same manner as that of magnet 8. In this way the arm 22 will have ample time to completely clear out the signal storing means A before the initial impulse of the second group of selecting impulses is received for effecting the operation of relay 5 and in consequence the energization of magnet 50 and the subsequent charging of the second set of condensers 16 to 20 inclusive, in accordance with the selecting impulses as transmitted over the line.

If it is desired to print an upper case letter, a special group of impulses will be transmitted over the line for causing the operation of relay 5 in accordance therewith and the condensers 11 to 15 or 16 to 20, depending upon the position of arm 7 of the distributor 6, will be charged accordingly. The shifting of type wheel 58 for performing such a function is controlled by magnets 47 and 48 which in turn are operated through the contacts of relay 63. The energizing circuit for the windings 51 and 52 of this relay is adapted to be established through the segments of the various rings of the translator switch and the right-hand armature of relay 30. Relay 30 determines which one of these windings 51 or 52, will be energized as the ground connection controlled thereby is adapted to be shifted from one contact to the other, depending upon its energization. It is to be noted that the printing magnet 38 is unaffected at this time, as certain ones of the selecting magnets will be so energized as to prevent the establishment of the energizing circuit for this magnet. The segments to which the windings 51 and 52 of relay 63 are connected are at the end of the travel of the translator arm 22 and are therefore not energized until this arm has nearly completed its cycle.

No means has been shown or provided for advancing the tape because any well-known method of spacing or line feed can be provided and since this does not form a part of the present invention it has been omitted for the sake of clarifying the drawing and the description relative thereto.

Referring now to Fig. 2 there is shown one form of construction of a printer for effecting the printing of the characters of a message in a continuous line. The arm 7 of the distributor 6 is frictionally connected

with the shaft 53 which is driven from the motor 54. The arm 7 is adapted, as before noted, to be held against rotation by means of holding pawls under the control of magnets 8 and 50. At one extremity of the shaft 53 there is keyed a gear 55 which drives another gear or pinion such as 56. Both of these gears are so proportioned with respect to one another that the speed of the one will be twice that of the other. The gear 56 is connected with a shaft 64 upon which is frictionally mounted the arm 22 of the translator switch 21 and the type shaft 57. This arm 22 is held against rotation by means of the holding pawl controlled by magnet 31. There is keyed to the shaft 57 the type wheel 58 and, inasmuch as the rotation of this shaft is under the control of the translator arm 22, the type wheel 58 will be rotated at a speed dependent upon the speed of the motor and the ratio of the gear reduction through which it is driven. An arrangement is shown in connection with the type wheel 58 which is controlled by means of the magnets 47 and 48 for shifting the type wheel from a lower to an upper case, or vice versa. The magnet 38 has attached to its armature a striker bar or hammer 59 which serves to press the tape 60 against the type wheel 58 upon the energization of this magnet.

A better understanding of the apparatus may be obtained from a description of the operation thereof and, for the sake of clearness, let us assume that it is desired to transmit the character D. This character may be represented by the following group of impulses, positive, negative, negative, positive and negative. It may also be assumed that there is a like distributor at the transmitting station, the same as that represented by the numeral 6 and which is adapted to rotate in synchronism therewith. A distant operator, in transmitting the letter D, would impress upon the line 4, a preliminary or initial impulse of a positive polarity which may be considered a starting impulse. This starting impulse thereby causes the operation of relay 5 which connects through its armature, the source of battery 10 with the winding of magnet 8. The connection of this source of battery with the winding of magnet 8 thereby causes its operation as the sources of battery connected thereto are now in series aiding and current, therefore, flow through the winding of magnet 8. The energization of magnet 8 thereby causes the attraction of the holding pawl and releases the arm 7 which is rotated by the motor 54. The contact arm 7 together with its brush in passing over the segments of the distributor places a charge on the condensers 11 to 15 inclusive, dependent upon the source of the current connected therewith through the armature of relay 5. Condensers 12, 13 and 15 will thus be charged negatively, while the remainder of those in group A will be charged positively. Selecting impulses are thus stored in the condensers which may be rendered effective for causing the operation of the selecting magnets. Immediately after the arm 7 has passed over the segment individual to the condenser 15 and makes contact with segment 61, magnet 31 will be energized over a circuit extending from battery through the winding of magnet 31, segment 61, arm 7 and brush connected thereto to the negative source of battery controlled by the armature of relay 5. This magnet 31 upon being energized attracts its armature and withdraws the holding pawl which holds the arm 22 against rotation. The arm 7 will, after passing over the segment 61 through which the magnet 31 is connected, be held by the holding pawl controlled by magnet 50 and will not be released until the initial impulse of the second group of selecting impulses is received at which time it will associate the various condensers in group B of the signal storing means with the armature of relay 5, in order that they may be charged in accordance with the incoming impulses.

The translator arm 22 in rotating, moves in the direction of the arrow and connects the condensers of group A with the winding of each of the selecting magnets individual thereto. Let us assume, for the sake of clearness, that the armatures of the selecting magnets are in their normally unactuated position and that the magnets to which current of a negative polarity is applied will be energized so as to attract their armatures and close their front contacts. As the brush arm of the translator switch continues its rotation, the selecting impulses stored in the set of condensers A will be consecutively applied to the selecting relays 26, 27, 28, 29 and 30 through circuits previously traced. Inasmuch as these relays are of the polarized type and respond to close their front contact only upon the application thereto of a negative impulse, for the particular example selected, selecting magnets 27, 28 and 30 will be energized to close their front contacts. With the armatures of these selecting magnets in this position and the continued rotation of the brush arm of the translator switch in the direction of the arrow, a circuit is completed upon the passing of the respective brushes over segments 41, 64, 65, 66, 67 and 68 for causing the energization of the printing magnet 38. Such a circuit may be traced from grounded battery 40 through segment 41, brush 23, segment 64, back contact of magnet 26, front contact of magnet 27, segment 65, brush 24, segment 66, front contact of magnet 28, back contact of magnet 29, segment 67, brush 25, seg-

ment 68, front contact of magnet 30 and the winding of printing magnet 38 to ground. When the translator brush arm is in this position, the character D, on the type wheel, which was desired to be printed, will now be in a position opposite the printing hammer 59 and inasmuch as the circuit for the printing magnet is at this time completed as just described, an impression 10 of the character D will be made on the tape 60. Blurring of the printed characters may be avoided by advancing the tape at the time of printing at a speed substantially equivalent to the speed of rotation of the 15 type wheel as shown in Patent No. 388,244 to Baudot, August 21, 1888. It is also to be noted that the arm 22 of the translator switch 21 will have passed over the first four segments of the translator 20 switch rings before the arm 7 of the distributor 6 is released to complete its cycle for associating the condensers 16 to 20 inclusive with the armature of relay 5 for causing the same to be charged in accordance 25 with the polarity of the current connected therewith. In this way, there is no danger of interference between the discharging of the first group of condensers and the charging of the second group as the 30 translator arm will have passed over the segments to which the condensers of the second group are connected.

What is claimed is:

1. A printing telegraph receiver comprising a plurality of groups of signal storing means, a distributor for allotting current impulses to said signal storing means, selecting mechanism, a translator switch

for consecutively associating said signal storing means with said selecting mechanism for effecting the operation thereof, and a printing magnet jointly controlled by said translator switch and said selecting mechanism for printing the characters of a message. 40

2. In combination a line, a relay associated with said line and operated by permutations of current impulses, a distributor, a translator switch adapted to make two revolutions to one of said distributor, means 50 operated by said distributor for causing the operation of said translator switch, printing means, and a plurality of selecting magnets controlled by said translator switch and energized by current impulses as received by said distributor for effecting the printing of the characters of a message in a continuous line. 55

3. A system of printing telegraphy comprising a line, a relay responsive to current 60 impulses transmitted over said line, current distributing means controlled by said relay, signal storing means associated with said distributing means, a plurality of selecting 65 relays, a translator switch for translating the effects of said signal storing means to said relays, a printing magnet, and an energizing circuit therefor completed through segments of said translator switch and contacts controlled by said selecting 70 relays for causing the printing of a desired character.

In witness whereof, I hereunto subscribe my name this 16th day of January, A. D. 1920.

JOHN H. BELL.
